GEORGE W. SLATER, OF NEW HAVEN, CONNECTICUT.

Letters Patent No. 63,660, dated April 9, 1867.

IMPROVEMENT IN BOW-IRONS FOR CARRIAGES.

The Schedule referred to in these Letters Patent and making part of the same.

TO ALL WHOM IT MAY CONCERN:

Be it known that I, GEORGE W. SLATER, of New Haven, Connecticut, have invented certain new and useful Improvements in Bow-Irons for Carriages; and I declare the following to be a full, true, and exact description of the same, reference being had to the accompanying drawings, which form a part of these specifications, and the letters of reference marked thereon.

Figure 1 represents a front view of the bow-irons.

Figure 2 represents the manner in which the back plate is attached to the frame.

Figure 3 represents a section view of one of the irons with the thimble or sheath attached.

Letter A represents the frame to which the bow-irons are attached and supported, and is secured to the side of the buggy or carriage by means of a screw or bolt which passes through the aperture B, made for that purpose. Letters C C C C represent the bow-irons, to which the wooden bows of the carriage are attached for the purpose of supporting the top or cover. These irons may be made of any malleable metal, and are fastened to the bed-plate or frame A by the means of rivets, which are cast upon the plate for that purpose. These rivets pass through the lower ends of the irons C C C C and are received into the back plate D, thus holding the irons firmly and securely in their places. The rivets are so cast upon the plate that they cannot be seen from either side. To each of the bow-irons is attached a thimble or socket, E, which receives the lower ends of the wooden bows of carriage top for the purpose of relieving the irons C of the great strain which bears upon the lower part. These thimbles are intended to be made of two pieces of a semicircular shape, one of each to be fastened to the sides of the iron C by means of a rivet cast upon it for that purpose. In the lower part of the bed-piece a is an opening, F, for the purpose of allowing the dirt and dust that may fall into the frame while the carriage is in motion to pass out, while it gives the frame a light and elegant appearance. Letter D represents the back plate of the frame, which is similar in shape to the front one. This plate, as shown by the red lines in fig. 2, is intended to be cast in the flange G in such a manner as to show no joint or edge on the bed-plate. The object of this is that no rough edge can be seen from the outside, giving it the appearance of being cast solid, while it makes it stronger.

The advantages of my invention consist in giving greater strength to the bow-irons by means of the thimbles, having a light and elegant appearance, and in doing away with a great part of the work by having the rivets cast upon the plate and saving labor in putting them together.

Having thus described my invention, what I claim, and desire to secure by Letters Patent, is—

1. The casting of rivets or projections upon the bed-plate a, substantially as and for the purpose set forth.
2. The thimbles E E, as constructed and applied, in combination with bow-irons C C, substantially for the purpose set forth.
3. The back plate D, in combination with the bed-plate a, when both are constructed as and for the purpose described.

In testimony that I claim the foregoing as my own I hereby affix my signature in the presence of two witnesses.

GEORGE W. SLATER.

Witnesses:

E. J. SANFORD,
C. B. BROOKS.
